(57) **CLAIM**

The ornamental design for a front fender for automobile, as shown and described.

DESCRIPTION

FIG. 1 is a perspective view of the front, left side and top of a front fender for automobile showing my new design;

FIG. 2 is a perspective view of the front, right side and top thereof;

FIG. 3 is a front side view thereof;

FIG. 4 is a rear side view thereof;

FIG. 5 is a left side view thereof;

FIG. 6 is a right side view thereof;

FIG. 7 is a top plan view thereof; and,

FIG. 8 is a bottom view thereof.

In the drawings, the broken lines show the rear portion of a front fender for automobile that form no part of the claim.
